INVENTOR

Kenneth D. Lighthype

UNITED STATES PATENT OFFICE.

KENNETH D. LIGHTHYPE, OF EAST ORANGE, NEW JERSEY, ASSIGNOR TO ELEVATOR SUPPLIES COMPANY, INC., A CORPORATION OF NEW JERSEY.

DESIGN FOR A SIGNAL FACEPLATE.

Application filed March 20, 1926. Serial No. 16,999. Term of patent 7 years.

To all whom it may concern:

Be it known that I, KENNETH D. LIGHTHYPE, a citizen of the United States, residing at East Orange, in the county of Essex and State of New Jersey, have invented a new, original, and ornamental Design for a Signal Faceplate, of which the following is a specification, reference being had to the accompanying drawings, forming part thereof.

Figures 1 and 2 are respectively front and side elevations of a signal faceplate, showing my new design.

Figure 3 is a top plan view thereof.

I claim:

The ornamental design for a signal faceplate as shown.

KENNETH D. LIGHTHYPE.
